CLAIM

The ornamental design for a combined container and compartment for holding coolants, as shown and described.

DESCRIPTION

FIG. 1 is a top right side perspective view of a combined container and compartment for holding coolants showing my new design;

FIG. 2 is a right side elevational view thereof with a portion cut away for clarity of illustration;

FIG. 3 is a left side elevational view thereof with a portion cut away for clarity of illustration;

FIG. 4 is a cross-sectional view thereof taken along line 4—4 of FIG. 1;

FIG. 5 is a top plan view thereof;

FIG. 6 is a bottom plan view thereof;

FIG. 7 is a front elevational view thereof; and

FIG. 8 is a rear elevational view thereof.
